CLAIM

The ornamental design for a turkey call, as shown and described.

DESCRIPTION

FIG. 1 is a front view of my new design; (rear view is a mirror image);

FIG. 2 is a partial side view thereof, taken on through 2—2 of FIG. 1; and,

FIG. 3 is a front view of another embodiment of FIG. 1, there are no ornamental design features for other views of this embodiment of the turkey call.

1 Claim, 2 Drawing Sheets

FIG. 3
